(57) CLAIM

The ornamental design for chair backrest, as shown and described.

DESCRIPTION

FIG. 1 is a perspective view of a chair backrest showing my new design;

FIG. 2 is a front elevational view of FIG. 1;

FIG. 3 is a rear elevational view of FIG. 1;

FIG. 4 is a left side elevational view of FIG. 1, the opposite side being a mirror image thereof;

FIG. 5 is a top plan view of FIG. 1;

FIG. 6 is a bottom plan view of FIG. 1; and,

FIG. 7 is another perspective view of FIG. 1. The broken lines showing the remainder of the chair are for illustrative purposes only and form no part of the claimed design.
